Inventor:
JAMES E. DOYLE

by his atty:

Conrad B. Mueller.

UNITED STATES PATENT OFFICE.

JAMES E. DOYLE, OF CLEVELAND, OHIO.

PRINTING-PRESS-HEATER SUPPORT.

Application filed March 20, 1920. Serial No. 367,450.

To all whom it may concern:

Be it known that I, JAMES E. DOYLE, a citizen of the United States, residing at 5718 Whittier Ave., in the city of Cleveland, county of Cuyahoga, and State of Ohio, have invented a new and useful Improvement in Printing-Press-Heater Supports, of which the following is a specification, the principle of the invention being 10 herein explained, and the best mode in which I have contemplated applying that principle so as to distinguish it from other inventions.

My invention pertains to a printing press heater support and more particularly a support having an electrical heater designed to present an incandescent resistance unit toward the path of movement of a freshly printed sheet of paper over the printing press.

According to the exemplification of the drawings, the support is adapted for use in conjunction with what has come to be well known as the "Miller feed" applied to a 25 Gordon type of press wherein one of two relatively movable frame members carries a chase upon which the typed form is mounted and the other frame member or support carries a platen adapted to swing toward 30 and away from the typed form. During the action of the illustrated parts, a sheet of paper after receiving an inked impression is taken hold of by suitable gripping fingers and drawn over and across the incandescent 35 heating surface so that it is thoroughly dried and static electricity removed.

Adverting to the drawings:—

Figure I is mainly a side elevation of the upper part of a Gordon press showing the platen carrying rocker in one position of its movement toward and away from the typed form over which inking rolls periodically pass, and also showing an electrical heater in section mounted thereon after the 45 manner of my invention. This figure further shows the printed paper sheet engaged by a gripping device and about to be withdrawn.

Figure II is a view corresponding to Figure I, with certain parts appearing in section showing a subsequent relation of the parts and specifically while the printed paper sheet is being drawn over the heater

preparatory to being released and deposited.

Figure III is a plan view on line III—III 55 of Figure II.

Figure IV is a broken section on line IV—IV of Figure I.

Figure V is a vertical section on line V—V of Figure III. 60

A frame member 1 carries a type-form 2 and in a position angularly related thereto also carries an inking disk 3. Distributor rolls 4 are adapted to roll over the disk 3 and the type-form 2 for the purpose of conveying ink from the former to the latter. The operation of a Gordon type of press being so old and well known in the art need not be enlarged upon, especially since the claims will not be restricted to combinations of standard parts of the press. 70

A support 5 relative to which the frame member 1 is adapted to swing carries a platen 6 with which the type-form 2 is adapted to come into engagement. It is 75 upon the platen 6 that sheets of paper P to be printed are laid and held by gripping fingers 7. The latter are adapted intermittently to be raised so as to permit the insertion or withdrawal of the sheet during such time when the type-form 2 and platen 6 are not in engagement. Carried by the support 5 is a movable arm 8 from which gripping fingers 9 depend. These fingers being likewise subject to automatic actuation and adapted to engage the upper end of the printed sheets so as to withdraw them from the plate and deposit them upon a table 10 provided with an adjustable ledge 11 carried by a bar 11^a having limited movement in a channel 11^b formed in the top of the table 10. Inasmuch as the action of the fingers 9 is also common knowledge in the art, it need be only added that the gripping engagement of the fingers 9 with the edges 80 of paper is automatically released whenever they reach the position shown in full lines in Figure II. Adjustably secured in suitable slots 12 in the ledge 11 by means of cap screws 12^a is a bracket 13 to which my incandescent heating unit 14 is detachably 90 connected.

Inasmuch as the electric heating unit 14 is 95 flexibly connected by means of a cord 15 with a source of current, its adjustment toward and away from the shelf 10 is per- 100 105

mitted. As will be readily understood such adjustment determines the proximity of the printed sheet to the source of heat.

I claim:—

5. 1. A device of the character described comprising a pair of members one of which is adapted to swing bodily relatively to the other, a part adjustably mounted upon one of said members, a heater adjustably carried by said part, and means carried by the other member adapted to draw a sheet over said heater.
10. 2. A device of the character described comprising a pair of members one of which is adapted to swing relative to the other, means carried by said swingable member adapted to draw a sheet along a prescribed path and a heater adjustably supported by one of said members and adapted for adjustment movement toward and away from said prescribed path.
15. 3. A device of the character described comprising a sheet depositing table, a platen movable relatively thereto, a sheet gripping device adapted to swing relatively thereto and adapted to transfer sheets from the latter to the former, and a heater adjustably carried by one of said first mentioned pair of elements in a position below the path of transfer movement of said sheet.
20. 4. A device of the character described comprising a sheet depositing table, a platen movable relatively thereto, a sheet gripping device also movable relatively thereto and adapted to transfer sheets from one to the other, and an incandescent heat unit adjustably attached to said table in a position below the path of transfer movement of said sheet.
25. 5. A device of the character described comprising a sheet depositing table, a platen movable relatively thereto, a sheet gripping device also movable relatively thereto and adapted to transfer sheets from one to the other, and an incandescent heat unit attached
30. to said table in a position below the path of transfer movement of said sheet, and means for effecting an adjustment of said unit in two distinct directions.
35. 6. A device of the character described comprising a pair of members one of which is adapted to swing relative to the other, an incandescent electric heater supported by one of said members, and means carried by the other member adapted to describe a path over said heater and to draw a sheet along with it.
40. 7. A device of the character described comprising a sheet depositing table, a platen mounted to swing relatively thereto, a sheet gripping device movable across said platen and in timed relation to the movement of the latter, said device being adapted to transfer sheets from one to the other, and a heat unit mounted in proximity to the path of transfer movement of said sheet.
45. 8. A printing press heater support comprising the combination of a table, a ledge adjustably connected with said table for movement along the latter, and a heater adjustably connected with said ledge for movement toward and away from said table.
50. 9. A printing press heater support comprising the combination of a table provided with a channel, a bar slideable in said channel and carrying an upstanding ledge fashioned with a slot, and a heater adjustably mounted for movement in said slot.
55. 10. A printing press heater support comprising the combination of a table and adapted for reciprocal movement in one plane, a member adjustably connected with said table and an incandescent heater adjustably mounted on said member and adapted for reciprocal movement in a plane which intersects said first mentioned plane.

Signed by me this 13th day of March, 1920.

JAMES E. DOYLE, Sr.
